United States Patent Office.

EDWARD N. CRANE, OF NEWARK, NEW JERSEY.

Design No. 3,394, dated March 2, 1869.

DESIGN FOR A BUCKLE-LOOP.

The Schedule referred to in these Letters Patent and making part of the same.

To all whom it may concern:

Be it known that I, EDWARD N. CRANE, of Newark, Essex county, New Jersey, have invented a new and ornamental Design for a Buckle-Loop; and I do hereby declare that the following is a full, clear, and exact description thereof, which will enable others skilled in the art to make and use the same, reference being had to the accompanying drawings, forming part of this specification.

My improvement consists in having the central portion of the loop provided with an open ornamental scalloped edge, substantially as shown in the drawings.

The figure is a perspective view of the buckle, in which *a* is the loop, having its central portion or in-

ner edges provided with an open ornamental scallop, *b*, as shown.

Having thus described my invention,

What I claim as new, and desire to secure by Letters Patent, is—

The ornamental design for a buckle-loop, substantially as described.

The above specification of my invention signed by me, this 12th day of December, 1868.

EDWARD N. CRANE.
